OILING SYSTEM FOR OUTBOARD MOTOR
DRIVE SHAFTS

Elmer Carl Kiekhaefer, Cedarburg, Wis.

Application December 17, 1948, Serial No. 65,807

2 Claims. (Cl. 123—196)

1

This invention relates to internal combustion engines and particularly to the lubrication of certain bearing members of two-cycle outboard marine engines.

A principal object of the invention is to provide for the supply of lubricant to certain bearing members during operation of the engine and for positive closing of the supply when the engine is not operating.

Another object is to provide a steady, uniform oiling of the drive shaft and other parts exposed to the exhaust gases of the engine to prevent corrosion of the parts.

Another object of the invention is to ensure a small reservoir of oil in the lower end of the crank-chamber at all times.

Another object is to prevent the excessive accumulation of oil in the lower end of the crank-case which interferes with the operation of the engine.

Another object is to prevent the leakage or discharge of the small oil reserve supply when the engine is stopped.

These and other objects and advantages of the invention will be more fully set forth in the following description of a preferred embodiment of the invention as illustrated in the accompanying drawing.

In the drawing:

Figure 1 is a side elevation of the upper part of an outboard motor with portions thereof broken away and sectioned;

Fig. 2 is a diagrammatic view looking upwardly toward the motor showing the relative positions of the oil passages and the engine piston at lower dead center and in an open position;

Fig. 3 is a view similar to Fig. 2 showing the piston between dead centers; and

Fig. 4 is a partial view similar to Fig. 1 of the lower crankcase bearing of the engine shown in Figure 1 with a single, valve-controlled drain passage.

The engine shown in the drawing comprises a crankcase 1 and cylinder block 2 provided with two parallel upper and lower cylinders 3 and 4. The vertical crankshaft 5 is journaled on upper and lower bearings 6 and 7 in crankcase 1 and carries the flywheel 8 at the upper end. The pistons 9 operating within respective cylinders 3 and 4 are connected to crankshaft 5 by the connecting rods 10. The center crankshaft bearing and valve unit 11 controls the induction of air and fuel including the engine lubricant from the carburetor 12 into the respective upper and lower crank chambers 13 and 14.

5 The two-cycle, two-cylinder engine is alternately fired by the spark plugs 15 and an electrical ignition system, not shown, operated by crankshaft 5 within flywheel 8. In the downstroke of each piston 9 the fuel within the respective crank chamber is compressed. The ports 16 and 17 in opposite sides of the cylinders 3 and 4 are uncovered by pistons 9 at the end of their downward stroke. The exhaust passage 18 in one 10 side of cylinder block 2 receives the exhaust from the cylinder through ports 16. A passage 19 in the other side of block 2 communicates with the respective crankcase chamber and provides for transfer of the compressed fuel from the chamber to the cylinder through ports 17. During the upward stroke of pistons 9 the fuel transferred to the respective cylinder is compressed for ignition while a new charge of air and fuel is drawn from carburetor 12 through valve unit 20 11 into the respective crank chamber.

The outboard motor drive shaft housing 20 supports the engine crankcase 1 and cylinder block 2 at its upper end and carries the propeller and underwater unit, not shown, at the lower end. The upper end of housing 20 is open and communicates with passage 18 opening downwardly of cylinder block 2 to receive the exhaust gases therefrom and discharge the gases under water.

25 The drive shaft 21 drivably connected to the propeller, not shown, extends vertically downwardly within housing 20 from the lower opening 22 of crankcase 1. The upper end of drive shaft 21 is splined as at 23 to fit within and engage the splined section 24 of the lower end of crankshaft 5.

30 The annular channel 25 around crankshaft 5 immediately below bearing 7 is provided to collect the heavier fuel deposited in the lower crank chamber 14. The portion of crankshaft 5 below bearing 7 may be provided with a running fit as at 26 with the lower end of crankcase 1 to seal the latter. The flange-type seal 27 shown in Fig. 4 may be provided to additionally prevent compression losses within the crank chamber.

35 According to the invention a vertical passage-way 28 is provided from lower crank chamber 14 extending downwardly therefrom which communicates with a chamber 29 inside the splined section 24 in crankshaft 5 through the passage 30 drilled radially through crankshaft section 24. The passage 31 from the lower side and crankcase end of cylinder 4 joins passage 29 to carry off excess oil on the inner wall of cylinder 4.

55 In the operation of the engine the drilled pas-

sage 30 registers with passage 28 at the lower dead center position of crankshaft 5 just before the pressure within crank chamber 14 has completely diminished so that a small amount of oil is positively discharged into chamber 29 with each crankshaft revolution. The oil passing into the chamber 29 lubricates the spline connection between shaft 5 and driveshaft 21 and passes downwardly and through opening 22 and into the driveshaft housing 20.

The compression in the upper cylinder 3 normally precludes the engine crankshaft 5 from stopping with passage 30 and the lower crank chamber 14 open to the atmosphere. The possibility of water or moisture entering the crank chamber and subjecting the bearings to corrosion is thus prevented.

When the engine is stopped after running, passage 30 is automatically closed by reason of the fact that the normal cylinder compression in upper and lower cylinders 3 and 4 causes the engine crankshaft 5 to come to rest approximately one-half way between upper and lower dead centers as shown in Fig. 3 or 180° from that shown.

By reason of the fact that passage 30 registers with passages 28 and 31 for only a small part of the cycle of compression in crank chamber 14 near the end of the discharge of fuel from the chamber into cylinder 4, the rate of flow through passages 28, 30 and 31 is held within the desired maximum limits at all speeds and so that there is substantially no loss of useful fuel compression and transfer.

Where the engine remains standing without use the closing of passage 29 prevents the drying of the bearing 6 and the loss of oil remaining in the lower end of the crankcase. When the engine is eventually started the small required amount of oil remaining in passage 28 will be available initially to lubricate the spline-bearing surfaces in opening 24 and prevent undue noise and wear. The positive discharge of oil prevents excessive amounts of oil to become accumulated within the crank chamber.

Various embodiments of the invention may be employed to lubricate various operating elements within the scope of the accompanying claims.

I claim:

1. In a two-cycle engine having two cylinders, a crankshaft with two corresponding opposite crank throws, a piston within each cylinder and connected to the respective crank throw for reciprocation in the cylinder, a separate crank chamber for each crank throw communicating with the end of the corresponding cylinder beneath the piston and adapted to receive the fuel mixture for precompression by the piston, fuel intake and exhaust ports opening into and from each cylinder and disposed to be closed by the respective piston and otherwise opened thereby with piston reciprocation remote from the combustion end of the cylinder, the combustion end of the cylinder being otherwise closed for compression of the gases therein by the piston and said crank throws being rotationally spaced 180° whereby a crank chamber associated with one cylinder is subject to a period of nominal com-

pression coinciding with a period of maximum compression in the combustion end of the other cylinder, a drain passage from the lower end of one of said crank chambers to provide a gravity discharge for lubricant and excess fuel therefrom, and a valve disposed to open said passage in timed relation with rotation of said crankshaft during said period of maximum compression in the cylinder associated with the other crank chamber, said valve otherwise closing said drain passage, the compression within said last-named cylinder being effective to bias said crankshaft to a position closing said valve and passage upon normal dissipation of inertia forces of the crankshaft when the engine is stopped.

2. In an outboard motor including a vertical drive shaft and a drive shaft housing therefor, a two-cycle engine having two cylinders and supported by said drive shaft housing, a crankshaft with two corresponding crank throws and having connection with the upper end of said drive shaft in said housing, a piston within each cylinder and connected to the respective crank throw for reciprocation in the cylinder, a separate crank chamber for each crank throw communicating with the end of the corresponding cylinder beneath the piston and adapted to receive the fuel mixture for precompression by the piston, fuel intake and exhaust ports opening into and from each cylinder and disposed to be closed by the respective piston and otherwise opened thereby with piston reciprocation remote from the combustion end of the cylinder, the combustion ends of the cylinders being otherwise closed for compression of the gases therein by the piston and said crank throws being rotationally spaced 180° whereby a crank chamber associated with one cylinder is subject to a period of nominal compression coinciding with a period of maximum compression in the combustion end of the other cylinder, a drain passage from the lower end of said last-named crank chamber to said crankshaft connection to utilize the lubricant and excess fuel to lubricate said connection, and a valve disposed to open said passage in timed relation with rotation of said crankshaft during said period of maximum compression in the cylinder associated with the other crank chamber, and said valve otherwise closing said drain passage, the compression within said last-named cylinder being effective to bias said crankshaft to a position closing said valve and passage upon normal dissipation of inertia forces of the crankshaft when the engine is stopped.
